UNITED STATES PATENT OFFICE.

FRIEDRICH HINKEL, OF NEW YORK, N. Y.

GAS-BRACKET.

SPECIFICATION forming part of Letters Patent No. 442,523, dated December 9, 1890.

Application filed August 21, 1890. Serial No. 362,622. (No model.)

To all whom it may concern:

Be it known that I, FRIEDRICH HINKEL, a citizen of the United States, residing at New York, in the county and State of New York, 5 have invented new and useful Improvements in Gas-Brackets, of which the following is a specification.

This invention relates to an improvement in gas-brackets; and by means of this invention a gas-bracket is obtained which can be readily adjusted and fixed in any desired position, as set forth in the following specification and claims, and illustrated in the annexed drawings, in which—

15 Figure 1 is a side elevation of a gas-bracket containing my invention. Fig. 2 is a plan view of Fig. 1. Fig. 3 shows the bracket in different adjustment than in Fig. 1. Fig. 4 is a section along x x , Fig. 1. Fig. 5 is a section along y y , Fig. 1. Fig. 6 is a section along z z , Fig. 1.

In the drawings, the letter A indicates a gas tube or pipe extending from the wall and having stop-cock B. To the tube A is connected a small tubular pivot C, carrying a limb D, which is connected to the pivot C by a pivot E, located horizontally at right angles to the latter. The pivot C allows the limb to be horizontally adjusted, and the pivot 25 E allows vertical or up and down adjustment of said limb. To the pivot E is connected a flange F, having a segmental slot G. Said slot is circularly arranged about the pivot E. A set-screw H passes through the slot G and 30 enters the tapped slide I, which can move or slide in the standard K, which is secured to the pivot C. The standard K guides the slide in its movements, and the movements of the slide compensate for any eccentricity of 35 the slot G. A second limb L is shown secured to the limb D in the same manner that the limb D is secured to the tube A. The limb 40

L is shown provided with a burner M. When the screws H H are loosened, the limbs D L can be adjusted vertically to any required 45 position and then fixed by tightening said screws. At the same time the pivots C C allow the limbs D L to be horizontally moved until the burner is in the required spot.

What I claim as new, and desire to secure 50 by Letters Patent, is—

1. The combination, with the wall tube or pipe A, having the vertical pivot C, provided with the standard K, of the tubular limb D, the horizontal pivot E, arranged at right angles to the said vertical pivot, connecting the limb with the latter, and provided with an attached flange F, having a segmental slot G concentric with said horizontal pivot, a movable slide I, guided by the standard on the 60 vertical pivot, and the set-screw H, passing through the segmental slot and engaging the slide, substantially as and for the purposes described.

2. A gas-bracket consisting of the wall tube 65 or pipe A, having the vertical pivot C, provided with the standard K, the limb D, the horizontal pivot E, arranged at right angles to and connecting the limb with the vertical pivot, and provided with a vertical flange F, 70 having a segmental slot G concentric with said horizontal pivot, a slide I, moving in the standard between the latter and the slotted flange, and the set-screw H, extending through the segmental slot of the flange and engaging 75 the slide to clamp the latter against the slotted flange, substantially as described.

In testimony whereof I hereunto set my hand in the presence of two subscribing witnesses.

FRIEDRICH HINKEL.

Witnesses.

Wm. C. HAUFF,
E. F. KASTENHUBER.
